CLAIM

The ornamental design for pliers for cutting cables, as shown and described.

DESCRIPTION

FIG. 1 is a front, top and left side perspective view of pliers for cutting cables, showing my new design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

The features shown in broken lines depict portions of the pliers for cutting cables that form no part of the claimed design.

1 Claim, 7 Drawing Sheets(56)
